UNITED STATES PATENT OFFICE.

SAMUEL MAYPER, OF NEW YORK, N. Y.

HOSE-SUPPORTER.

SPECIFICATION forming part of Letters Patent No. 783,881, dated February 28, 1905.

Application filed December 9, 1904. Serial No. 236,107.

To all whom it may concern:

Be it known that I, SAMUEL MAYPER, of the city, county, and State of New York, have invented a new and Improved Hose-Supporter, 5 of which the following is a full, clear, and exact description.

My invention relates to improvements in hose-supporters, and more particularly to combination hose-supporters and abdominal or 10 hip pads. In devices of this kind it has been the practice to make the pad portion of the device in practically one piece; but in practice such a construction does not work to the best advantage.

15 The object of my invention is to produce a device in which a plurality of pads are used and in which these are supported from the waist in such a way that the draft between the waist-line and the hose will be such as to 20 bring the bearing parts of the pad against the right portions of the body and with the best effect. In a single pad no adjustment or little adjustment is possible; but with the plural pads as I use them they can be adjusted so 25 that the draft will be in the best place for ease or pressure, and the parts can be adjusted back and forth in relation to each other on their supporting-belt, so that they can be made to fit the body to a nicety. Moreover, if de- 30 sired, the pads can be slipped apart so that they will not bear across the abdomen, but will extend downward from the hips, and it will be seen, therefore, that I provide for a nice adjustment to suit people of different 35 shapes or inclinations.

To these ends my invention consists of certain features of construction and combinations of parts, which will be hereinafter described or claimed.

40 Reference is to be had to the accompanying drawings, forming a part of this specification, in which similar figures of reference indicate corresponding parts in both the figures.

Figure 1 is a perspective view showing the 45 application of the whole supporter to the body and hose, and Fig. 2 is a perspective view showing how the pads are adjusted when they lie over the hips.

The device has a belt 10, which can be made 50 of webbing or of any suitable material, and the belt has fastening means, such as a buckle

11, to enable it to be fastened around the waist. The belt carries a pair of oblong pads 12, which are adapted to cross each other, as shown in Fig. 1, and which to this end are made slightly 55 bias, and each pad has a plurality of slots 13, through which the belt 10 is passed and which are located near the top of the pad. This arrangement causes the pad to be securely held; but, if desired, other means can be used for 60 fastening the pad and belt together without departing from the principle of the invention. The arrangement described, however, permits the pads to be very readily adjusted back and forth on the belt in relation to each other. 65 The arrangement just described also forms a very secure attachment between the pad and the belt, and as the pad is directly attached to the belt and slidably thereon it hangs better than where intervening or connecting devices 70 between the pad and belt are used, and it dispenses with all metallic or similar fastenings, which are always objectionable. The pads at their lower edges carry the hose-supporting straps 14, which can be of any usual kind and 75 which can be provided with any usual fastening device at 15 to secure them to the stockings.

It will be seen that by crossing the pads, as in Fig. 1, they make an excellent abdominal 80 supporter, and it will be understood that the adjustment provides for fitting any usual figure, and it will be further seen that if an abdominal pad is not desirable the pads 12 may be slipped apart, as in Fig. 2, and permitted 85 to hang over the hips. In either case the device is easily applied; easily adjusted, and serves its purpose perfectly.

Having thus fully described my invention, I claim as new and desire to secure by Letters 90 Patent—

A device of the kind described, comprising a waist-belt, a pair of pads, each pad having a pair of vertical slits to receive the belt so as to slide freely thereon and so arranged as 95 to cross each other or be freely separated on the belt, and hose-supporting devices on the lower portions of the pads.

SAMUEL MAYPER.
